UNITED STATES PATENT OFFICE.

HARRY H. WIGGLESWORTH, OF PHILADELPHIA, PENNSYLVANIA, ASSIGNOR TO THE PHILADELPHIA DRYING MACHINERY COMPANY, OF PHILADELPHIA, PENNSYLVANIA, A CORPORATION OF PENNSYLVANIA.

DRYING MACHINE.

Application filed May 28, 1924. Serial No. 716,329.

This invention relates to drying machines and more particularly to a hosiery drier including an enclosure and a continuous guideway over which detached form carriers are traversed in vertically aligned relation with capacity for exterior exposure for stripping and clothing.

This invention further aims to provide a compact machine of the above typified character of considerable capacity and great efficiency due to the undulatory or zig-zag course traversed by the form carriers while progressed through the drying enclosure.

Other objects and attendant advantages inhering to my invention will be hereafter referred to, or become apparent from the following detailed description of one practical embodiment thereof, which has been chosen to illustrate the aggrouped characteristics and mode of operation.

In the further disclosure of this invention reference is had to the accompanying sheets of explanatory drawings, constituting a part hereof, and in which corresponding features are distinguished by the same designating characters in all the views.

Fig. I, is a side elevation of a hosiery drier conventionally in accordance with this invention, with part broken away to disclose certain underlying components.

Fig. II, is a top plan view with parts removed, or in section, to better evidence certain enclosed structural features; and,

Fig. III, is a transverse vertical section taken approximately on the line III—III in the preceding figure.

In accordance with the organization illustrated, which is particularly adapted for the drying of hosiery, I construct a rectangular framework of standard section verticals and rigidly attached horizontals 5, 6 respectively, surrounded by thermo-insulated panels 7 to provide an enclosure 8—in spaced relation above the floor level 9—with a roof 10 and bottom 11. This enclosure 8 is subdivided by a plurality of longitudinal partitions 12, in spaced parallelism between the roof 10 and bottom 11, with opposed elongated apertures 13 therein, and a connected diaphragm 14, whereby a zig-zag drying corridor 15 is provided through which detached form carriers 16, are intermittently progressed, as hereafter fully explained.

The roof 10 of the enclosure 8 is fashioned with an invert frusto-pyramidal recession 17, and concentrically below the same, a housing 18 for a horizontally rotatable fan 19, is fitted in the diaphragm 14. This fan 19 is attached to a vertical shaft journaled in a bearing 20 mounted within the recession 17, and it is adapted to be rotated through the medium of a miter couple 21, in turn driven by a countershaft 22, journaled in bearings 23, securely attached upon the roof 10 aforesaid. Rotary motion is transmitted to the countershaft 22, by a belt drive 24 from any convenient source of power, and said countershaft is also fitted with a second pulley 25 instrumental, through the medium of an endless transmission 26, to impart motion to a horizontal shaft 27, journaled in bearings 28, rigidly supported by the machine sub-framework.

Referring to the detached form carriers 16 which are adapted to removably support hosiery forms 29, it will be seen that the shoe portions 30 thereof are of rectangular configuration to traverse a substantially continuous trackway 31, of opposed coplanar angle sections rigidly supported in parallelism below a centrally aligning race or slot 32 formed in the bottom 11 of the enclosure 8. This race or slot 32, it is to be remarked, is of a width to admit free passage of the form carriers 16, as hereafter more fully explained, while the shoes 30 may be fitted with ball castors or rollers to minimize friction. In addition to the foregoing each form carrier 16 is provided with a depending stud 33 for co-operative engagement by an associate lug-link 34 in an endless conveyor chain 35, trained about horizontally rotatable and staggered sprocket wheels 36, 36' journaled in bearings 37, mounted in a sub-framework 38, interconnected with the main framework of the machine, but affording a laterally projecting substantially rectangular support 39, at the front of the machine. Idler sprocket wheels 40, are journaled in appropriate bearings for horizontal rotation relative to the corners of the support 39, and to establish a continuous course for the conveyor chain 35, as will be readily appreciated by anyone in the least acquainted with the art to which this invention appertains.

Progressive motion is imparted to the con-

veyor chain 35, by means of a worm-wheel 41 splined upon the shaft of the sprocket wheel 36, meshing with a worm 42, on the horizontal shaft 27, hereinbefore referred to; and it will be quite obvious that by suitably proportioning the respective gears involved, said chain 35 may be traveled with a comparatively slow motion for reasons hereafter referred to; or, dwell spaced instrumentalities—not shown—may be substituted so that the conveyor chain 35 is intermittently progressed.

Appropriate vertical radiators 43 are fitted—for example—within the outer laps—hereinafter designated the ingress and egress avenues *a*, *b* respectively—of the drying corridor 15, through which the heating medium is circulated in accordance with common practice. Furthermore, the front panel 7, of the enclosure 8, is provided with vertical entry and exit slots 44, 45 respectively, of sufficient width to permit free passage of the hosiery forms 29 edge-on; while it is noticeable that the aforesaid race or slot 32 is reinforced or beaded at its edges to prevent buckling, as well as to afford a better guidance relative to the form carrier clamping upper edges, as will be best understood by an examination of Fig. III more particularly. Still further it is to be observed that the endless conveyor 35, is afforded planal support to prevent "sag" by a channel section guide-way 46 aligned with its progressive course, as will be readily understood without further detailed descriptive matter.

Having set forth the distinguishing structural features of this invention, the operation thereof may be briefly summarized as follows. Assuming that rotary motion is communicated to the countershaft 22, it will be apparent that the fan 19 is continuously driven, whereby the drying medium is circulated transversely of the zig-zag corridor 15, within the enclosure 8, with duplex directional flow, as conventionally indicated by the arrows appearing on Fig. III. Simultaneously the transverse shaft 27, will be continuously revolved and through the worm drive 42, 41 impart comparatively slow progressive motion to the endless conveyor 35, whereby the series of detached form carriers 16—and hosiery forms 29 removably mounted thereon—will be successively entered through the vertical slot 44, and gradually advanced along the ingress avenue *a* relative to the drying corridor 15. Continued motion will result in the hosiery forms 29 slowly progressing along the race 32, over the trackway 31, along a zig-zag continuous course until they pass the egress avenue *b*, and emerge through the vertical exit slot 45 over the laterally projecting support 39. Now, if it is assumed, that a stripper-operative is stationed at "S" and

a boarder-operative at "B" (Fig. II), as the emerging hosiery forms 29 approach the angular corner of the projecting support 39 it will be obvious that the dried article can be removed with facility at the station "S." Continued movement will swing the form 29, around an angle of ninety degrees, wholly clear of the following form advancing to stripping location. Further progression of the conveyor 35, will travel the consecutively stripped forms 29, to the boarding position, "B" whereat the attendant operative will re-clothe the same with fresh wet hose, prior to said forms re-entering the drying corridor 15 by way of the vertical slot 44. Incidentally, it may be noted that the reclothing operation is best effected while the form 29 is angularly progressing—as shown—whereby greater freedom for operative manipulation to properly align the hose on the form is afforded.

From the foregoing it is thought that the sequence of operations will be fully appreciated without further explanatory matter, while the attendant advantages are obvious without specific mention. The right is hereby reserved to make such changes and necessary alterations as will adapt my novel drying machine for treating other articles than hosiery; such modificatory evolutions being limited, however, to the reasonable scope of the subjoined claims.

Having thus described my invention, I claim:

1. A drying machine comprising an enclosure having apertured partitions and a connected diaphragm affording a vertical drying corridor, detached form carriers traversible edge-on over a zig-zag course through said corridor in sequential alignment, and a horizontally traveling conveyor for progressing said carriers through the enclosure with an interval of exterior exposure for the purposes specified.

2. In a drying machine, an enclosure having spaced partitions and a connected diaphragm providing a vertical circuitous drying corridor, a series of detached form carriers traversible edge-on through the corridor in aligned sequence, a horizontally traveling conveyor for progressing said form carriers through the enclosure with an interval of exterior exposure, and means circulating a drying medium transversely of the circuitous corridor with duplex-directional flow.

3. In a drying machine, an enclosure having parallel partitions with a connecting diaphragm affording a vertical drying corridor, said partitions having opposed elongated apertures therein, individual form carriers traversible therethrough along a zig-zag path and a horizontally operating conveyor effective to sequentially progress the form carriers through the drying corridor with an

interval of exterior exposure for the purposes specified.

4. In a drying machine, an enclosure having parallel partitions with a connecting diaphragm affording a vertical drying corridor, said partitions having opposed elongated apertures at one end, a series of individual form carriers traversible therethrough along a zig-zag path, a horizontally operative endless conveyor effective to sequentially progress the form carriers in

aligned vertical relation through the drying corridor and over a substantially rectangular course exterior thereto to effect stripping and reclothing, and means circulating a drying medium transversely of the aforesaid corridor with duplex-directional flow. ¹⁵

In testimony whereof, I have hereunto signed my name at Philadelphia, Pennsylvania, this 23rd day of May, 1924.

HARRY H. WIGGLESWORTH.
